Primary Examiner — Kelley Donnelly*(74) Attorney, Agent, or Firm* — Lerner, David, Littenberg, Krumholz & Mentlik, LLP**CLAIM**

I claim the ornamental design for a finger grip for furniture, as shown and described.

DESCRIPTION

FIG. 1 is a top perspective view of a finger grip for furniture showing my new design;

FIG. 2 is a front view thereof;

FIG. 3 is a back view thereof;

FIG. 4 is a left side view thereof, the right side being a mirror image;

FIG. 5 is a top plan view thereof; and,

FIG. 6 is a bottom plan view thereof.

The broken lines showing in FIGS. 1 through 5 are for the purpose of illustrating the environment of the design and form no part of the claimed design.
